UNITED STATES PATENT OFFICE.

WILLIAM LEWIS CROWELL, OF DANIELSON, CONNECTICUT.

PLACE-HOLDER FOR BOOKS.

1,273,038.

Specification of Letters Patent. Patented July 16, 1918.

Application filed February 9, 1918. Serial No. 216,328.

To all whom it may concern:

Be it known that I, WILLIAM L. CROWELL, a citizen of the United States, residing at Danielson, in the county of Windham, State 5 of Connecticut, have invented a new and useful Place-Holder for Books; and I do hereby declare the following to be a full, clear, and exact description of the invention, such as will enable others skilled in the art 10 to which it appertains to make and use the same:

The present invention relates to a place holder for books, and has for its object to provide a device of this character which 15 embodies novel features of construction whereby it can be readily applied to an opened book without danger of defacing or injuring the same, and will hold the book in an open position with the pages spread 20 out substantially flat so that the printed matter thereon can be read without annoyance or difficulty.

Further objects of the invention are to provide a place holder for books which is 25 comparatively simple and inexpensive in its construction, which can be readily placed in position or removed therefrom, which can be easily manipulated to admit of the pages of the book being turned as desired, and 30 which can be utilized for advertising purposes.

With these and other objects in view, the invention consists in certain novel combinations and arrangements of the parts as 35 will more fully appear as the description proceeds, the novel features thereof being pointed out in the appended claims.

For a full understanding of the invention, reference is to be had to the following description and accompanying drawings, in 40 which:

Figure 1 is a top plan view of the upper portion of an open book, the device being shown as applied to the book in such a manner as to retain it in an open position.

Fig. 2 is a detached perspective view of the device, one of the advertising cards being shown as partially withdrawn.

Fig. 3 is an enlarged horizontal sectional view through one of the said wings of the device, taken on the line 3—3 of Fig. 2.

Fig. 4 is an enlarged vertical sectional view on the line 4—4 of Fig. 2.

Fig. 5 is a detail view of one of the card 55 receiving plates, and

Fig. 6 is a detail view of one of the angu-

lar portions of the wire body upon which the card receiving plates are mounted.

Corresponding and like parts are referred to in the following description and indicated in all the views of the drawings by the same reference characters.

Specifically describing the present embodiment of the invention, the numeral 1 designates an elongated U-shaped wire body 65 which is adapted to be inserted between the pages 2 of a book A. The two sides of the U-shaped wire body have the upper ends thereof offset forwardly, as indicated at 3 and returned laterally in opposite directions 70 at 4 in a plane substantially parallel to and spaced from that of the lower portion of the body. The lower ends of the returned portions 4 of the wire are extended laterally at 5 in the plane of the returned portions, thereby providing substantially L-shaped arms or wings upon which the sheet metal plates 6 are mounted. These plates 6 are substantially rectangular in shape and have the lower sides and inner ends thereof 80 rolled around the L-shaped wire arms, as indicated at 7, the extreme edges of these rolled portions of the plates being extended over the body of the plate and offset outwardly therefrom to provide retaining 85 flanges 8 which coöperate with the returned upper edges 9 of the plates to receive cards 10 upon which any desired advertising matter may be printed. As indicated by Figs. 2 and 3, these cards 10 are readily removable by sliding them through the outer ends of the plates, and the cards of any merchant or business man could be readily inserted in position, thereby enabling the device to 90 be used very advantageously for advertising purposes.

When using the device the U-shaped body portion 1 is inserted between the pages of the book and the laterally extending wings or plates 1 caused to fit over the upper edges 100 of the pages of the book at the place where the book is opened. These lateral wings have a sufficient spread to extend appreciable distances on opposite sides of the back binding of the book at which the book is 105 opened. The device thus serves to hold the book in an open and substantially flat position, so that the printed matter on the pages can be read without difficulty or annoyance, even though the book may be new and have 110 a stiff binding so that the pages have a tendency to spring together instead of re-

maining in an open position. In order to turn a page of the book it is merely necessary to slide the device upwardly until after the page is turned, the device being then moved back to its original position.

Having thus described the invention, what I claim as new and desire to secure by Letters Patent, is:—

1. A place holder for books including a wire stock having a looped back adapted to be inserted between the pages of an open book at the back thereof, an end of the wire being returned and terminating in an L-shaped arm arranged in a plane parallel to and offset forwardly from the looped back of the body, and a plate applied to the L-shaped arm and having edge portions rolled around the sides thereof to retain the plate in position.
2. A place holder for books including a U-shaped wire body adapted to be inserted between the pages of an open book at the back thereof, oppositely extending L-shaped arms carried by the sides of the U-shaped body at the upper end thereof, said L-shaped arms being arranged in a plane parallel to and offset forwardly from that of the lower portion of the body, and plates applied to the L-shaped arms and each having a side and an end thereof rolled around the respective L-shaped arm, the extreme edges of the rolled portions of the plate being extended

over the plate in a spaced relation thereto to provide card retaining flanges, while one of the opposite edges of each of the plates is returned to provide a coöperating card retaining flange.

3. A place holder for books including a U-shaped wire body adapted to be inserted between the pages of an open book at the back thereof, the sides of the U-shaped body having the upper ends thereof offset forwardly and returned in a plane parallel to and spaced from that of the lower portion of the body, the extremities of the returned ends being extended laterally in opposite directions to provide L-shaped arms, and plates applied to the L-shaped arms, each of the plates having a side and end thereof rolled around the respective L-shaped arm and the extreme edge of the rolled portion being extended over the plate in a spaced relation thereto to provide a card retaining flange, while an opposite edge of the plate is returned to provide a coöperating card retaining flange.

In testimony whereof I have signed my name to this specification in the presence of two subscribing witnesses.

WILLIAM LEWIS CROWELL.
